TOY RAILROAD ROUNDHOUSE

Robert I. Genin, New Rochelle, and Leon S. Wirch,
Forest Hills, N.Y., assignors to Child Guidance Toys,
Inc., Bronx, N.Y., a corporation of New York

Filed May 25, 1961, Ser. No. 65,342

Term of patent 14 years

(Cl. D34—15)

FIG. 1.

FIG. 5.

FIG. 2.

FIG. 3.

FIG. 4.

FIGURE 1 is a top plan view of the toy railroad roundhouse showing our new design,

FIG. 2 is a side elevational view,

FIG. 3 is a right end elevational view,

FIG. 4 is a transverse sectional view looking in plan on the track and as viewed on line 4-4 of FIG. 2, and

FIG. 5 is a left end top perspective view thereof.

We claim:

The ornamental design for a toy railroad roundhouse, substantially as shown.
